UNITED STATES PATENT OFFICE.

RANDALL H. JONES, OF INDIANAPOLIS, INDIANA.

DESIGN FOR A RING.

Application filed September 19, 1924. Serial No. 10,831. Term of patent $3\frac{1}{2}$ years.

To all whom it may concern:

Be it known that I, RANDALL H. JONES, a citizen of the United States of America, residing in the city of Indianapolis, county of Marion, and State of Indiana, have invented a new, original, and ornamental Design for Ring, of which the following is a specification, reference being had to the accompanying drawing, forming a part thereof.

In the drawings Fig. 1 is a top plan view of the ring. Fig. 2 is a side elevation thereof.

I claim:

The ornamental design for a ring, as shown.

RANDALL H. JONES.
